CLAIM

I claim the ornamental design for a mouse sleeve, as shown and described.

DESCRIPTION

FIG. 1 is a perspective view of a mouse sleeve;
FIG. 2 is a front view of the mouse sleeve of FIG. 1;
FIG. 3 is a rear view of the mouse sleeve of FIG. 1;
FIG. 4 is right side view of the mouse sleeve of FIG. 1;
FIG. 5 is a left side view of the mouse sleeve of FIG. 1;
FIG. 6 is a top view of the mouse sleeve of FIG. 1;
FIG. 7 is a bottom view of the mouse sleeve of FIG. 1; and,
FIG. 8 is a perspective view of the mouse sleeve of FIG. 1 shown fit over a mouse.

The broken lines shown in the drawings are included for purposes of illustrating environment and form no part of the claimed design. The surface shading lines show contour and/or distinguish between open and solid areas. The surface shading lines are not surface ornamentation.
